UNITED STATES PATENT OFFICE.

OLOF NILSEN, OF HOBOKEN, NEW JERSEY.

DAVIT FOR LIFE-BOATS.

1,170,315.

Specification of Letters Patent.

Patented Feb. 1, 1916.

Application filed September 19, 1914. Serial No. 862,471.

To all whom it may concern:

Be it known that I, OLOF NILSEN, a citizen of the United States, of the city of Hoboken, in the county of Hudson and State 5 of New Jersey, have invented certain new and useful Improvements in Davits for Life-Boats; and I do hereby declare the following to be a full, clear, and exact description of the invention, such as will enable others skilled in the art to which it ap- 10 pertains to make and use the same.

The primary object of my invention is to provide improved means for swinging a life boat from the inboard to the outboard position or vice versa.

I attain the primary object of my invention by providing a single connecting element or lever fulcrumed to the two davits and shift this element by appropriate means 20 which effects the proper relative movement of the davits to properly swing the boat.

In the accompanying drawing, Figure 1 is a view in side elevation showing the boat deck and passenger deck of a ship in conventional arrangement. Fig. 2 is a top plan view with the boat deck broken away. Figs. 25 3 and 4 illustrate the positions of the parts in operation.

Referring to the drawing I have shown 30 the life boat 1 mounted upon a pair of cradles 1^a which are hinged to the boat deck so that they may be turned down and allow the boat to be suspended solely from the davits and swung clear of the deck.

35 At 2 I have shown a vertically mounted shaft which may extend through the two decks and be provided with an operating knob or handle 3 at its upper end which latter is above the boat deck. This shaft 40 carries a sprocket 4 around which passes a sprocket chain 5. This sprocket chain also passes over idler sprockets 6, 7 and 8, mounted in bearings in the lower face of the gun deck.

45 The lever 9 constitutes the only connection between the davits and is directly and positively operated by the sprocket chain. I have shown the lever secured to the sprocket chain as at 10, a pin 12 being se- 50 cured to the lever and to one of the links of the chain.

On each of the davits is keyed a laterally disposed arm 13, each of which is fulcrumed to one extremity of the lever.

55 The direction of movement of the lever

consequent upon the course taken by the chain in moving over the sprockets, swings the davits in the customary way, that is, on first starting both davits are swung in one direction until the bow or stern of the life 60 boat has reached the outboard position, after which the other davit is swung outward. The lever is thus provided with substantially a conveyer and a guide to insure its taking the desired course. When the 65 davits are in the outboard position a notch 14 in the lever is engaged by a lug 15 shown depending from the boat deck and the davits are locked as against further turning in the outboard direction. When in inboard 70 position the lever engages one of the davits as at 16 and prevents further movement.

The sprocket chain may move through suitable brackets or guides 17 and it is desirable to provide a pair of brackets 18 for 75 the lever in the event that its weight might cause it to sag.

The mechanism for lowering and raising the boat forms no part of my invention. I have illustrated a winch 19, however, whose 80 barrels receive the falls from the sheaves on the davits in the usual manner. It is only desirable that this winch shall be located adjacent the operating device 3 so that one deck hand may perform all the 85 necessary work of swinging the davits as well as raising and lowering the boat. To do this he does not have to change his position, and it will be noted that the swinging of the davits is accomplished by the simple 90 continuous turning of the wheel or handle 3 in one direction and that the same is true when swinging the davits to the other position, the only difference being the direction in which the part 3 is turned to accomplish 95 the two purposes.

It will be obvious that my invention is extremely simple and effective. I am enabled to dispense with all changeable gear devices by which one davit is first swung 100 and then the other. In consequence I am enabled to swing the davits very quickly. The mechanism may be cheaply manufactured and installed and contains no parts likely to become deranged through lack of 105 use or broken by sudden operation.

I claim as my invention:—

1. In a life boat apparatus, a pair of davits, a single lever connecting said davits, a conveyer attached to said lever, and means 110

- for moving said conveyer to shift said lever and swing said davits to the outboard or inboard positions.
2. In a life boat apparatus, a pair of davits, a lever connecting said davits, a sprocket chain secured to said lever, and means for operating said sprocket chain to shift said lever and swing said davits to the outboard or inboard positions.
- 10 3. In a life boat apparatus, a pair of davits, a single lever connecting said davits, means for shifting said lever, and a guide for causing said lever to follow a predetermined path in its shifting movement to swing said davits successively to the outboard or inboard positions.
- 15

4. In a life boat apparatus, the combination with a pair of davits, of a shaft having an operating device located adjacent said davits, a sprocket wheel on said shaft, a 20 series of idler sprockets, a chain passed over all of said sprockets, and a lever connecting said davits and secured to a link of said chain.

In testimony whereof, I have signed this 25 specification in the presence of two subscribing witnesses.

OLOF NILSEN.
